UNITED STATES PATENT OFFICE

STEPHEN CZENCZ, OF BUDAPEST, HUNGARY

TOOTHBRUSH

Application filed December 10, 1926, Serial No. 153,892, and in Hungary December 12, 1925. Renewed February 19, 1930.

This invention relates to a toothbrush. It is generally aimed to provide an improved construction which is relatively inexpensive and has bristles arranged in a novel manner to effectively engage all surfaces of the teeth.

In addition, an object is to provide a new form of brush head using spaced ribs serving dually to reinforce the head and constituting attaching means for a handle.

Additional objects and advantages will in part be pointed out and in part become apparent in considering the following description in connection with accompanying drawings illustrating an operative embodiment, and wherein

Fig. 1 is a side elevation of the toothbrush; Fig. 2 is an end elevation of the toothbrush; Fig. 3 is a plan view of the toothbrush, and Fig. 4 is a transverse section taken through the brush head alone along the line of the handle-engaging sockets.

Referring specifically to the drawings wherein like reference characters designate like or corresponding parts in the several views, a generally H-shaped head or body member is provided at A which may be made of celluloid. Said head has backs 1 and 2 which are joined intermediate their ends by a wall or connecting member 3. Bristles 6 and 7 extend from the backs 1 and 2, respectively, toward each other and in the manipulation of the brush head are adapted to engage the opposite surfaces of the teeth. The biting surfaces of the teeth are engageable by bristles 8 extending from opposite sides of the wall 3 toward the ends of the backs 1 and 2, but terminating short thereof.

The head A is manipulated by means of a handle 4 having a pair of laterally extending lugs 5 which are swivelled in sockets 9 provided in the inner surfaces of spaced ribs 10 formed longitudinally along the back 1 to reinforce such back and constitute fastening means for the handle.

In attaching the handle 4 to the back A, the latter is heated whereby the ribs 9 are rendered pliable for separation to receive the lugs 5 and to be thereafter restored to original

position, whereby the head and handle will be operatively connected.

It will be realized that the bristles 6, 7 and 8 will simultaneously clean all surfaces of the teeth as the brush head is drawn over them and that it is not necessary to remove the head A from the mouth as when changing the zone of operation because the handle 4 can be shifted on its lugs to the extent of 180° and at each terminal of its movement will rest against the back 1.

Changes may be resorted to provided they fall within the spirit and scope of the invention as defined by the appended claim.

I claim as my invention:—

A tooth brush head having a body member provided with spaced portions constituting backs, bristles extending from the backs toward each other, a connecting member for said backs spaced from the respective ends thereof and having bristles on opposite sides thereof extending toward said ends, one of said backs having spaced, outwardly extending, longitudinal ribs thereon disposed at substantially a right angle to said connecting member to generally reinforce the head and having sockets facing each other to constitute attaching means for a handle.

In testimony whereof the foregoing specification is signed.

STEPHEN CZENCZ.
